Arthur B. Jenkins
ATTORNEY

UNITED STATES PATENT OFFICE

GEORGE A. LONG, OF HARTFORD, CONNECTICUT, ASSIGNOR TO THE LONG SECURITY LOCK COMPANY, OF HARTFORD, CONNECTICUT, A CORPORATION OF CONNECTICUT

LOCK AND KEY THEREFOR

Application filed November 18, 1927. Serial No. 234,258.

My invention relates to that class of devices that are employed for securing doors and similar closures, and an object of the invention, among others, is the provision of means for simplifying the act of operating a lock for said closures.

One form of device embodying my invention and in the construction and use of which the objects herein set out, as well as others, 10 may be attained, is illustrated in the accompanying drawings, in which—

Figure 1 is a face view of my improved key.

Figure 2 is an end view of the same.

Figure 3 is a face view showing one of the 15 key members partially removed from the other member and completely removed from a lock.

Figure 4 is an isometric view showing the 20 two key members substantially separated.

Figure 5 is a face view of a lock used in 25 connection with my improved key.

Figure 6 is an edge view of the same.

Figure 7 is a view similar to Figure 5, but 30 with the cover plate removed to show the interior mechanism.

Fig. 8 is a view similar to Fig. 7 but showing the locking bolt in its unlocked position.

Fig. 9 is a view in section on a plane denoted by the dotted line 9—9 of Fig. 7.

Many locks in use at the present time embody mechanism so arranged that at least two keys must be used to operate the mechanism for the purpose of gaining access to the compartment closed by the door or other closure to which the lock is affixed. Such instances are common in the case of safe-deposit boxes or similar compartments in 35 banks and other places wherein a key possessed by the custodian or guard of the box is required to effect a partial rotation of the key center or barrel, and the key of the person renting the box is required to complete 40 the operation to release the locking element. In this operation the key of the custodian must be first inserted and the operation partially performed thereby. The key of the custodian must then be removed before the 45 key of the person renting the box can be 50

inserted, this in another opening whereupon the operation of unlocking the box is completed.

By the use of my improved key illustrated and described herein this operation is greatly 55 simplified in that only one operation is required to effect opening movement of the lock mechanism, this embodying one insertion only of the key. In attaining this result I so arrange the lock mechanism that 60 a single opening only is required for the key, such key comprising a plurality of separable members, two of such members being employed in that development of the invention illustrated and described herein, wherein 65 in the drawings the numeral 10 indicates a lock case for containing the locking mechanism, such mechanism, generally speaking, comprising at least two sets of tumblers. The tumblers in the various sets may be of different 70 types, and the sets of tumblers may be variously arranged, the mechanism illustrated herein very satisfactorily answering the purpose and embodying a set 11 of pin tumblers placed in a well known manner in connection with a barrel or key center 12 rotatably 75 mounted in the case and a set of flat or leaf tumblers 13 pivotally mounted in the case. The pin tumblers are operated by the key to release or secure the barrel or key center, 80 and the flat or leaf tumblers operate to release or secure the locking bolt in a manner that will be readily understood.

My improved key is composed preferably of two members 15—16 divided lengthwise 85 and having means for removable insertion of the members within the key center or barrel that is rotated to operate the locking bolt 14. In the structure herein shown the key member 15 is bitted or notched to receive the pin tumblers and the member 16 is provided with angularly shaped bits and notches properly arranged to operate the leaf or flat tumblers. When the key has been operated to completely rotate the barrel 90 the member 15 may be removed, the member 16 being retained in the barrel and, in fact, being secured therein against removal 95 when the locking bolt 14 is thrown back.

Each of the members 15 and 16 has a re- 100

taining notch 17 to receive a lip 18 extending around the central opening in an escutcheon 19, in which opening the outer end of the key center or barrel 12 is located. Entering notches 20 are formed in the lip 18, as shown in Fig. 5, and a key releasing notch 21 is also formed in said lip.

In order that the two members of the key may be securely, temporarily held together one of said members, as the member 16, has a sloping shoulder that the end of the section 15 is fitted to. A thumb piece 23 of the section 15 has an elongated lug or rib 24 that is received in a slot 25 in a thumb piece 26 of the key member 16. A bridge 27 closes the end of the slot 25 and is arched, as shown in Fig. 4, thereby forming a groove 28 to permit passage of the lug 24 underneath said bridge.

In the operation of the key in connection with the lock mechanism, for instance as that of a safe deposit box, the custodian or guard takes the separable key member 16 from the possessor of the box and attaches it to the separable key member 15 in the custody of said guard, and as shown in Fig. 1. The completed key is then inserted in the lock having the parts in the position shown in Fig. 7 of the drawings. The key member 15 will place the pin tumblers 11 with their ends all flush with the mouths of their respective openings, thus enabling the barrel or key center 12 to be rotated. The key is now turned in a clockwise direction to the position shown in Fig. 8, wherein the shoulder on one side of the notch 17 will be located opposite the releasing notch 21, and the key member 15 may be removed by sliding it relatively with respect to the key member 16, and as illustrated in Fig. 4. The key member 16 of the box owner, however, cannot be removed when in this position for the reason that the inner shoulder of its notch 17 is against the inner surface of the lip 18.

The operation above described, however, has unlocked the door, the mechanism parts being in the position shown in Fig. 8, and said door may be opened. When the door is again closed all that is required to lock it is to turn the key member 16 that has been retained in the lock in a contra-clockwise direction, or to the left, when the locking members will be returned to the position shown in Fig. 7 and the box door will be locked. The key member 16 may now be readily removed from the lock.

It will thus be seen that in the place of two keys I have produced a single key composed of two members, and the complete key is operated in the same manner as a single key, but at the end of the unlocking operation one member of the key may be removed, leaving the other key member to be made use of in the locking operation.

It will be noted that the blades of the two key members are located in the same plane by offsetting one or both of said blades from the plane of its thumb piece. In the structure herein shown the blade of the key member 16 is entirely offset from the plane of its thumb piece into the plane of the blade of the key member 15.

It may here be briefly stated that the lock herein shown is of that type wherein the tumblers 13 have notches adapted to register with detents 29, to permit the locking bolt to be drawn back, the tumblers of that part of the set 11 not located in the barrel 12 being located in a tumbler block 30. The barrel 12 has an arm 31 to enter a notch in the side of the locking bolt for the purpose of moving said bolt when permitted by the tumblers 13 which are properly located for that purpose by the bits in the key member 16.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A key comprising a plurality of members separable lengthwise thereof and adapted for independent operation of different sets of lock tumblers, means for uniting said members for joint operation of a lock mechanism, and means to permit separation of said members and removal of one from within the lock and thereafter the locking operation of the lock by the other member.

2. A key comprising a plurality of members separable lengthwise thereof, means for uniting said members in the same plane for joint operation of a lock mechanism, means to permit separation of said members when in the lock mechanism by sliding one lengthwise in the plane occupied by it when united to the other member, and means for effecting locking operation of the lock after removal of one of said members.

3. A key comprising two members separable lengthwise thereof and fitting each other edge to edge, one of said members having an opening, a projection on the other of said members adapted to fit said opening to temporarily unite said members and align them transversely and means for aligning said members in another direction.

4. A key comprising two members separable lengthwise thereof and fitting each other edge to edge, each of said members having a thumb piece and one of said thumb pieces having a slot, a rib on the other thumb piece shaped to fit said slot to tem-

porarily unite said key members and align them in a transverse direction and means for aligning said members in another direction.

5 5. A key comprising two members separable lengthwise thereof and fitting each other edge to edge, each of said members having a thumb piece and one of said thumb pieces having a slot and a releasing groove opening out of said slot, and a rib on the other thumb piece shaped to fit said slot to temporarily unite said key members for joint operation of a lock mechanism, said rib being formed to pass through said groove for separation of said key members.

10 15 6. A key comprising two members separable one from the other, means on one of said members for operating one set of tumblers, means to then permit separation and removal of one of said members from the other while in a lock mechanism, and means on the other member for operating another set of tumblers.
